US00D380962S

United States Patent [19]

Trigger

[11] Patent Number: Des. 380,962

[45] Date of Patent: **Jul. 15, 1997

[54] PACKAGE

[75] Inventor: **David Trigger**, Shouldham, England

[73] Assignee: **Ethical Pharmaceuticals Limited**,
United Kingdom

[**] Term: **14 Years**

[21] Appl. No.: **40,659**

[22] Filed: **Jun. 20, 1995**

[30] Foreign Application Priority Data

Dec. 21, 1994 [GB] United Kingdom 2044041

[51] LOC (6) Cl. **09-07**

[52] U.S. Cl. **D9/415**
